UNITED STATES PATENT OFFICE

129,912

DESIGN FOR A TEMPLE FOR AN OPHTHALMIC MOUNTING

Theodore R. Uhlemann, Antioch, Ill., assignor to
Uhlemann Optical Co. of Illinois, Chicago, Ill.,
a corporation of Delaware

Application April 5, 1940, Serial No. 91,489

Term of patent 3½ years

To all whom it may concern:

Be it known that I, Theodore R. Uhlemann, a citizen of the United States, residing at Antioch, in the county of Lake and State of Illinois, have invented a new, original, and ornamental Design for a Temple for Ophthalmic Mountings, of which the following is a specification, reference being had to the accompanying drawing, forming a part thereof, in which

Fig. 1 is a perspective view of a temple for ophthalmic mountings showing my new design;

Fig. 2 is a section on the line 2—2 of Fig. 1.

I claim:

The ornamental design for a temple for an ophthalmic mounting, substantially as shown.

THEODORE R. UHLEMANN.
